Specification of Letters Patent.

Patented Oct. 30, 1917.

Application filed July 27, 1917. Serial No. 183,099.

To all whom it may concern:

Be it known that we, ARTHUR DARDEN and FELIX F. DOERING, citizens of the United States of America, residing at Anniston, in the county of Calhoun and State of Alabama, have invented certain new and useful Improvements in Track-Laying Machines, of which the following is a specification.

Our invention relates to a track laying machine comprising one or more cars carrying suitable equipment for loading, storing and unloading cross ties and rails in the manner best calculated to facilitate the rapid construction of railway tracks.

One object of our invention is to improve the mechanism for loading, storing and unloading rails and to this end the car is provided with rollers which are vertically adjustable and upon which the rails can be moved onto or off from the car which carries separate supports onto which the rails are loaded in tiers, the rollers being adjustable to receive the rails from or deliver them to the different tiers. These supports for the tiers of rails rest on the tier of rails next under it and support the tier of rails above it so that they will slide freely laterally in being stacked or removed, and after all rails are removed from over a support it is free 30 to be swung out of the way to facilitate the handling of the rails beneath it.

A further object of our invention is to improve the means for supporting the ties in position to be conveniently handled by an endless conveyer, this feature of our invention comprising a series of hinged angles connected to longitudinal Z-bars or equivalent elements and adapted in one position to support the ties above the endless conveyer and in the other position to swing clear of the path of the ties and permit them to be moved in either direction by the conveyer.

A further object of our invention is to improve and perfect the mechanism for controlling, tensioning and equilizing the parallel endless conveyer cables or chains utilized to handle the cross ties.

A further object of our invention relates more particularly to a track laying machine which comprises two cars, the rear car carrying a cab for the power plant and part of the tie and rail supporting and handling mechanism, and the forward car carrying the remainder of the cross tie and rail supporting and handling mechanism together with the

downwardly sloping front end extension for delivering or receiving the cross ties and rails close to the ground level. Where cars are thus coupled and parallel conveyers are employed for moving the ties, it will be evident that in rounding curves the conveyers will tend to work against one or the other of the side of the guides or bars carrying the tie supports. To avoid this the supports are designed so that they diverge from the cab 60 toward the front end of the rear car and converge from the rear end of the forward car toward its front end, the angles of divergence being sufficient to leave the conveyers free of engagement therewith in 65 rounding any normal curve and yet keeping the tie supports always sufficiently close to support the cross ties above the conveyers.

A further feature of our invention relates to means for adapting the front inclined extension to receive a long coupling bar whereby the car or cars can be coupled to a locomotive or to other cars at the front.

Our invention further comprises the various novel details of construction and arrangements of parts which in their preferred embodiment only are illustrated in the accompanying drawings forming a part of this specification, and in which:

Figures 1 and 2 show the rear car in plan and side elevations, respectively.

Figs. 3 and 4 show the front car in plan and side elevations, respectively.

Figs. 5 and 6 are half end elevations of the car, one showing a cross tie supported above the conveyer and the other showing it resting on the conveyer.

Fig. 7 is a detail elevation partly broken away of the adjustable roller supports.

Figs. 8 and 9 are enlarged detail plan and side views of the driving and adjusting means for the endless conveyers.

Figs. 10 and 11 are plan and side elevations of the adjustable sprockets for the front conveyer chains.

Similar reference numerals refer to similar parts throughout the drawings.

In describing our invention, it will be noted that the machine as a whole may be considered as consisting of one or more than one car, but it will be described as consisting of two cars suitably coupled together by a steel bar 1 which is pivotally connected in any suitable manner to the center sills 2 of the cars. Each car comprises two trucks 3 110

which are pivotally connected by center bearings to the center sills and being of standard form wheel design need not be described in detail. The body of each car consists of a center sill built of side channels 4 and top and bottom plates 5 and 6, respectively, the rear end of the center sill of the rear car carrying a coupler 7 and any standard mounting therefor. To the bottom of the center sills are riveted a number of transverse steel bunks 8, 9 and 10. The bunks 8 being those which overlie and are pivotally connected to the trucks and thus serve to support the car body and its load. The bunks 9 are disposed between the bunks 8 on each car and the bunk 10 is connected to the downwardly inclined front extension of the front car. The several bunks are all suitably braced to the center sills by steel bars or angles 11 and the bunks 9 and 10 are also supported by bent straps 12 which pass under them and are bent up on each side and riveted to the center sills. The bunks are also preferably built of two channels reinforced by plates and separators in the manner well understood in this art. At each end of the bunks 8 and 9 (except the rear bunk 8 on the rear car), is mounted a casting 13 which is disposed between and riveted to the side channels and forms a guide or socket for a casting 14 which may be raised or lowered therein. The adjustment of the casting 14 is accomplished by turning a shaft 15 journaled to rotate in the casting 13 and having connected thereto the upper end of a chain 16, the lower end of which is attached to a pin 17 at the bottom of the casting 14. The casting 14 is hollow to receive the chain and has its side walls provided with vertically elongated slots 18 in which the shaft 15 works. The shaft 15 is held in any desired position by means of a ratchet wheel 19 fast on the shaft and engaging a pawl 20 carried by the casting 13. In the upper end of the casting 14 a roller 21 is mounted to rotate on a shaft 22 made fast in the casting and is so arranged that the top edge of the roller will project above the top edge of the casting 14 but will be a few inches below the top of the raised side flange 23 which serves as a guard to prevent a rail sliding off the outer end of the roller. The upper edges of the bunk channels opposite the castings 14 are cut away as shown at 24, Fig. 6, in order to permit the casting to be lowered sufficiently so that in its lowest position the top of its roller will be even with the top level of the bunk, as more clearly seen in Fig. 5. The upper part of the casting 14 is made with a large sloping surface 25 on each side of the roller 21, which surface starts slightly below the top of the roller and continues on a downward and outward slope toward the front and rear of the car to about four and one-half

inches below the top of the roller. The guard flanges 23 extend to the outer ends of these sloping surfaces 25 but with gradually diminishing height. The rear bunk 8 on the rear car is shorter than the other bunks and besides the usual center castings and side bearings it carries only the sheave frames 26 (Fig. 9) bolted to its upper surface and disposed one on each side of the center sill. The bunk 10 placed near the outer end of the front sloping extension 27 of the forward center sill carries at each end a non-adjustable roller 28 running on a shaft 29 supported by two castings 30 which extend a few inches above the top level of the rollers to serve as an end guard and prevent the rails sliding off. An idler sprocket 31 is also suitably mounted upon the top of the bunk 10 on each side of the extension 27.

To the top of each center sill is riveted a frame-work of angles and Z-bars comprising a series of Z-bars 32 and 33, the latter being of varying length and all being riveted to the top plates of the center sills. These bars all lie parallel in the same plane and to their tops on each car are riveted two longitudinal divergent Z-bars 34 which are farthest apart at the ends where the two cars are coupled together and which are closest together at the opposite ends of the cars. The bars 32 extend the full width of the car and at their outer ends carry the running boards 35.

The longitudinal bars 34 carry angles 36 and 37, the angles 36 being riveted thereto and bolted to the cab 38 which is mounted on the rear end of the rear car. The angles 37 are hinged to the bars 34 in oppositely disposed pairs by means of hinge members 39 and 40, the hinge member 39 being bent at right angles at an intermediate point and riveted to the upper face of the angle while the hinge member 40 is riveted to the underface of the top member of the bar 34. These angles 37 are of short lengths having separate hinges for each length. In raised position the angles 37 will rest upon and project above the bars 34 while in their lowered position they will swing outwardly and downwardly below the top level of the bars 34.

The center sill of the rear car is straight but the center sill of the forward car is bent down at an angle and has connected thereto an extension member 27 built up of plates and angles which are spliced to the channels and top plate of the center sill in a manner to insure a strong rigid splice. We rivet to the outer end of the extension 27 a heavy angle 41 which extends transversely and supports four bent angles 42, two of which are arranged on each side of and parallel with the extension 27 and which slope upward at about the same slope as the top edge of the extension, 130

and are riveted at their upper ends to four other angles 43 which in turn are riveted to the lower flanges of the two front Z-bars 32, 33. These angles 43 carry suitable bearings (not shown) for the cross shaft 44 and are suitably braced together and tied into the car body in any suitable manner to give firm and rigid support. A cross bar 45 is riveted to the top of the extension and extends out far enough on each side to support the angles 42 at the center.

The cab 38 is made up of any suitable construction and incloses a steam engine 46 which receives its supply of steam through a pipe 47 from the locomotive that at the time is handling the track car. The engine drives a small gear 48 which meshes with a large gear 49 (Fig. 9) mounted on a shaft 50 which runs in bearings cast integral with the sheave frame 26. On each end of the shaft 50, just outside of the sheave frames, we mount a rope sheave 51 which constitutes the driving sheave. In front of and slightly below each driving sheave is an equalizing sheave 52 mounted on its respective shaft 53 which is fitted into an equalizer block 54. The equalizer blocks are pivotally fastened to each end of an equalizer bar 55 which passes laterally across the car and works in longitudinal slots provided therefor in channels 56 which are riveted to the center sill channels 4. The blocks 54 are free to slide longitudinally on the top edges of the sheave frame sides and are provided with suitable guides to hold them on their tracks. The equalizer bar 55 is pivoted at its center to a yoke 57 fitted onto a screw 58 which passes through a beveled gear 59, a backing plate 60, between two springs 61, and through a follower plate 62 which is engaged by the head of the screw bearing on its outer face. The beveled gear 59 meshes with a beveled gear 63 which is held in place by a shaft 64 which passes upwardly through a guide plate 65 attached to the top of the backing plate 60. This shaft, at its upper end, is provided with a hand wheel 66 or other suitable operating means located within the cab. The backing plate 60 is held by lugs 67 riveted to the channels 56 and the whole is supported by angles 68 riveted to the channels 56.

Below each equalizing sheave 52 is placed a tightening sheave 69, each tightening sheave being mounted on a separate shaft 70 fast on a tightening block 71 which is arranged to slide longitudinally in an elongated slot 72 in the side of the sheave frame 26, being prevented from coming out by suitable side guides. A screw shaft 73 extends longitudinally through each slot 72, passing freely through its respective tightening block 71, and a spring 74 beyond the block and through a nut 75 beyond the spring. A beveled gear 76 is mounted on

each screw shaft 73 adjacent to its rear bearing in the sheave frame and the rear exposed end of the shaft is made square to receive a turning tool. A shaft 77 is mounted at its lower end in each sheave frame and carries a beveled gear 78 which meshes with the beveled gear 76. The upper ends of the shafts 77 project into the cab and may be turned by any suitable means (not shown). An idler sheave 79 is mounted near the forward end of each sheave frame and two small idler sheaves 80 and 81 are mounted on the top of each sheave frame. By turning the screw shafts 73 either by use of a wrench on their outer square ends, or by turning the shafts 77, the tightening sheaves 69 can be adjusted to tighten or loosen the endless ropes or conveyors 82.

Two endless conveyors 82 are used, all-steel ropes or cables being preferably employed, and all arranged to run longitudinally along the cars on each side between the divergent bars 34 and above the bars 32, 33. The ropes pass over and under the idler sheaves 80, 81, and thence over the upper rollers 85 of both cars, and thence around the sheaves 84 near the extension 27 and return over the bottom rollers 83 of both cars. The sheaves 84 are fast on the shaft 44 on which are mounted two sprockets 86, each disposed between a pair of the angles 43. Two endless chains 87 pass around the sprockets 86 and over idlers 88 supported on the angles 42 and thence over tightening sprockets 89 (Figs. 10 and 11), running on shafts 90 supported by angles 91 riveted to the under forward ends of the angles 42. Slots are provided in the angles to allow for the longitudinal movement of the shafts 90 of each sprocket when it is necessary for tightening the chains, this movement being accomplished by means of a screw 92 made square at its outer end and passed through a nut 93 and through the end angle 94 connecting the forward ends of the angles 42. The head of each screw has a bearing against the inside of a yoke 95 which straddles the sprockets 89 and has round bearing holes for the sprocket shaft 90 so that the shaft and sprocket will move with the yoke responsive to the screw. The chains after passing around the sprocket wheel 89 return to the driving sprockets 86. These chains have short projections or spurs 96 disposed at intervals along their upper edge.

The bottom rollers 83 on the cars are preferably made of heavy pipe having small castings 97 which are shrunk into each end and have alining openings through which a shaft 98 is inserted. The shafts are supported by small angles 99 riveted to the bottom flange of the Z-bars 34 and are held by cotter pins at each end. The upper rollers 85 are similarly constructed having end 130

castings 97^a and shafts 98^a which are inserted through holes drilled in the Z-bars 34 and are held in place by cotter pins at each end.

5 All of the idler sheaves, sprockets and rollers are preferably provided with screw plugs and adapted to be charged with lubricant so as to make the shaft on which they turn well lubricated.

10 Each car is provided with a plurality of separator bars 100 preferably eight being placed on each side of each center sill in sets of two near each bunk 8 or 9. These separator bars are preferably made of steel 15 and have their outer ends bent down about one-half inch, their inner ends being perforated so that a pin or bolt 101 can be passed through the same and through the top and bottom flanges of the center sill 20 channels 4 and removably secured in place in any suitable manner. The separator bars, as thus arranged, are free to be swung horizontally to positions parallel with the center sills or at right angles thereto, in which 25 latter position their outer ends come adjacent to the line of the inner ends of the castings 14 carrying the rollers 21.

The cars are also preferably provided with boxes 102 suitably suspended from the 30 center sill below the bunks. On top of and about the center of the forward extension 27 is a forged plate or casting 103 into which one end of a long coupling pole 104 may be inserted so that the cars may be coupled to 35 a locomotive or other cars in front and moved thereby when desired.

Operation.

Assuming the cars to be coupled to each 40 other and to a rear locomotive from which steam is supplied to the pipe 47, the engine 46 may be started up and caused to drive the endless ropes 82 by means of the gears 48 and 49 and sheaves 51. The tightening 45 sheaves 61 are then adjusted to bring the proper tension on the ropes and the tightening sprockets 89 are adjusted to take out all unnecessary slack in the sprocket chains 87. The track cars are then moved to a point 50 where the rails are stored and the rails are loaded thereonto one at a time, the ends of each rail being adjusted on the end roller 28 and then pushed along on the same until its end will engage the roller 21 in the forward 55 casting 14, after which the rail is pushed along until it balances on the first roller 21, after which it assumes horizontal position and is pushed along over the rollers 21 to the rear car. It is then pushed laterally off 60 the rollers over the tops of the bunks 8 and 9 and over against the center sill. This is continued until the whole loading space of the bunks is occupied, when the four lower separator bars 100 on each side are placed 65 across and on top of the first tier of rails,

the castings 14 are then raised by turning the shafts 15 and winding up the chains 16 until all are held at the proper height for delivering the rails onto the separator bars. The rails are then brought in again and 70 stacked on top of the separator bars until the second tier of rails is completed, whereupon additional separator bars are moved into place and the third tier of rails stacked thereon, and so on, there being as many 75 separator bars as there is place for tiers of rails under the Z-bars 32.

The cars are then taken to the point where cross ties are kept and the engine 46 is started to running so that the upper strands of 80 ropes 82 and conveyer chains 87 move toward the cab on the rear car. The ties are then placed laterally across the ends of the angles 42 which form a shelf for holding one or two ties at a time. The ties are 85 then pushed along the top of the angles until they come into position to be engaged by the spurs 96 on the chains 87 and moved thereby longitudinally and upwardly along the forward extension 27 and onto the front 90 car. The ties then pass over the sprockets 86 onto the ropes 82 which carry them back across the forward and rear cars to the fixed angles 36 on the rear car where men standing 95 on the running boards 35 lift off the ties and stack them on the angles 36. When these angles have been loaded with ties the two hinged angles 37 adjacent thereto are turned up on top of the Z-bars 34 and ties are stacked thereon until these angles are 100 filled. This process is repeated, the successive pairs of angles 37 being filled from the rear forwardly until the full load of ties is 105 on board. The ties when supported on the angles 36 and 37, allow the upper strands of the ropes 82 to pass freely under them. All necessary fish plates, spikes, bolts and tools are placed in the tool boxes 102 and the cars are now pushed forward to the end of the existing track, the forward car being 110 placed so that the ends of the angles 42 are approximately over the end of the track. The engine 38 is then reversed to start the cables and chains moving away from the cab and toward the forward end of the front 115 car. Two men on the running board 35, one on each side, begin placing ties one at a time on top of the ropes 82 which deliver the ties to the sprocket chains 87 which deliver the ties onto the projecting ends of the angles 120 42, from which point other men take the ties and place them on the road bed in proper spaced relation. When sufficient ties have been laid to receive a length of rail, the engine is stopped and the men take the outer 125 rail of the top tier on each side of the front car, push it laterally onto the adjacent rollers 21 which stand at the proper level to receive it (see Fig. 6), and then pull the rail along the rollers until its outer end drops 130

onto the roller 28. The rail is pulled out on this roller and is then lifted into place and spiked, the same operation taking place in delivering rails on each side of the car.

5 The foregoing relationship of the Z-bars 34 will permit the ropes 82 to have a certain amount of lateral play to allow for successful working on a curved track.

When the cars are on a curved track they 10 assume an angular position to each other with the result that the distance between the driving sheave 51 on the rear car, and the sheave 84 on the forward car is greater on one side than it is on the other, which, if 15 not provided for, would result in undue tension on one rope if not actual breakage. This variation is allowed for by the equalizer bar 55 which, pivoted at its center, will allow the equalizing sheave block 54 with 20 sheave 52 to move so as to keep both ropes 82 at a proper working tension under all conditions of curved track, thereby equalizing the tension on the two ropes 82.

This equalizer bar 55 with both the equalizing blocks 54 and sheaves 52, may be moved bodily to either tighten or loosen both ropes 82 at the same time. This is of special advantage to quickly relieve both ropes of any tension whatever for traveling, thereby 30 saving wear and tear on the ropes, and for quickly bringing the ropes to working tension when operations are to begin.

As the ropes 82 will gradually stretch and get longer, due to the tension and to wear, 35 the sheaves 69 may be so moved by means of the screw 73 so that each rope may be individually brought to the proper tension.

The springs 61 which are compressed by a pull on the equalizer bar 55, and the 40 springs 74 which are compressed by a pull on the tightening sheave 69 and block 71, keep the ropes taut, resulting in a good driving contact on the driving sheave 51. These springs also allow for sudden variations in the tension of the ropes.

It has been mentioned that the roller housing castings 14 are provided with sloping surfaces 25 on each side of the roller 21. In pulling rails along the top of the rollers 50 21 it may happen that one end of the rail on account of some unevenness in the rail or in the car, may strike the side of a roller 21 and come to a stop were it not for the sloping surfaces 25 which would guide the 55 end of the rail up to the top of the roller 21 without jar or loss of time.

While we prefer to supply steam to the engine in the cab from the locomotive boiler, it will be understood however that the track 60 car may be adapted to generate its own steam and the engine may be provided with additional gearing or other machine elements adapted to drive any other moving parts of the car as well as the car itself. 65 The motive power may differ from steam

engine, a gasoline, oil engine, electric motor, or motor of any other type being substituted.

Having thus described our invention, what we claim as new and desire to secure by Letters Patent, is:—

1. In a track laying car, a skeleton body comprising transverse structural metal bunks adapted to support rails, a center sill above and connected to said bunks, short tie supporting bars mounted on said center sill and 75 spaced thereby above said bunks sufficiently to clear a plurality of tiers of rails stacked on the lower bunks, and vertically adjustable roller bearers mounted on the outer ends of the bunks.

2. In a track laying car, a skeleton structural metal body comprising a longitudinal center sill and series of upper and lower cross bearers made fast to the center sill which passes between them, an endless conveyer traveling above the upper cross bearers, roller supports for the conveyer, separator bars for rails disposed to work between the series of cross bearers, and roller supports for rails at the outer ends of the 80 lower cross bearers.

3. A track laying car comprising a body adapted to support a plurality of tiers of rails, and movable separator bars vertically 85 adjustably mounted on said body and adapted to be interposed between the tiers of rails.

4. A track laying car comprising a body adapted to support a plurality of tiers of rails, movable separator bars adapted to be interposed between the tiers of rails, and vertically adjustable anti-friction supports 90 which are movable into position to receive rails from different tiers.

5. A track laying car comprising a body 105 adapted to support a plurality of tiers of rails, movable separator bars adapted to be interposed between the tiers of rails, and vertically movable roller bearings adapted to be adjusted to the levels of different tiers 110 of rails and into position to receive rails from said separator bars.

6. In a track laying car, a body adapted to support tiers of rails, castings each carrying a roller, a guide in which the castings 115 are vertically movable, and means to hold said castings at different levels to receive rails from different tiers on said rollers.

7. In a track laying car, a body adapted to support tiers of rails, castings each carrying a roller, a guide in which the castings are vertically movable, a chain connected to the castings, a rotatable shaft having fixed bearings and connected to the chain, and a pawl and ratchet means to lock the shaft 125 and hold the castings in the desired position by the chain.

8. In a track laying car, a body adapted to support tiers of rails, castings each carrying a roller journaled in its upper end, 130

guides in which the castings are vertically movable, and means to adjust the castings to bring the top of the rollers substantially on a level with the bottom of any tier of 5 rails.

9. In a track laying car, a skeleton body comprising upper and lower transverse members spaced to permit tiers of rails to be mounted between them on the lower members, guides at the outer ends of said lower members, a roller bearing casting vertically adjustable in each guide, and means to hold 10 said castings at the levels to receive rails from the several tiers of rails.

10. In a track laying car, a skeleton body comprising transverse rail supporting bunks, a guide casting attached to the outer ends of the bunks at a lower level than the top 15 of the bunk, and a roller bearing casting vertically adjustable in each guide and in 20 its lowest position standing level with the top of the bunk.

11. In a track laying car, a body comprising rail supporting bunks having cut away 25 seats and vertical guides at their outer ends, and castings having bodies adjustable in the guides and heads adapted to be received in said seats, rollers journaled in said heads and standing substantially flush with the 30 top level of the bunks when the casting head is seated thereon, and means to hold the castings at different operating levels.

12. In a track laying car, a car body adapted to support tiers of rails, a plurality 35 of vertically adjustable elements mounted on the car body and comprising heads having guide faces sloping to front and rear of the car, and rollers mounted at the apices of the heads and forming a rail runway, substantially as described.

13. In a track laying car, guides, castings vertically adjustable in the guides and comprising hollow bodies and inverted V-shaped heads, rollers journaled at the apices of the 45 heads, chains working in the hollow bodies and connected thereto, a shaft journaled in each guide and connected to a chain, the bodies being cut away to move free of engagement with said shafts, and pawl and 50 ratchet means to lock the shafts.

14. In a track laying car, a skeleton structural metal body comprising bunks adapted to support tiers of rails, rollers mounted in the outer ends of the bunks to form a runway for the rails, and inclined guides sloping downwardly to front and rear of the car on each side of the rollers.

15. In a track laying car, a skeleton structural metal body comprising bunks adapted 60 to support tiers of rails, a casting mounted in the outer ends of the bunks and having sloping guide faces which extend substantially below the top of the casting and face to front and rear of the car, and rollers 65 mounted to project slightly above the top

level of the castings and form a rail runway.

16. In a track laying car, a center sill, a plurality of rail supporting bunks underhung from the sill, and two series of cross bearers mounted on the sill, one set extending the full width of the car and carrying running boards, and the other set extending less than the width of the car, longitudinal cross tie supports mounted on the cross bearers of both sets, an endless conveyer means working between said supports, and means to drive said conveyer.

17. In a track laying car, a center sill, a plurality of rail supporting bunks underhung from the sill, and two series of cross bearers mounted on the sill, one set extending the full width of the car and carrying running boards, and the other set extending less than the width of the car and of gradually increasing length, divergent longitudinal cross tie supports mounted on the cross bearers of both sets, an endless conveyer means working between said supports, and means to drive said conveyer.

18. In a track laying car, trucks, a center sill of structural metal, rail supporting bunks underhung from the center sill, and a cross tie supporting superstructure mounted on the center sill and comprising transverse Z-bars resting on the sill, and longitudinal Z-bars resting on the transverse Z-bars, an endless conveyer means working between the longitudinal Z-bars, and movable cross tie supports mounted on said longitudinal Z-bars.

19. In a track laying car, trucks, a center sill of structural metal, rail supporting bunks underhung from the center sill, and a cross tie supporting superstructure mounted on the center sill and comprising transverse Z-bars resting on the sill, and longitudinal Z-bars resting on the transverse Z-bars, an endless conveyer means working between the longitudinal Z-bars, roller supports for said conveyer means journaled in said superstructure, and movable cross tie supports mounted on said longitudinal Z-bars.

20. In a track laying car, trucks, a center sill of structural metal, rail supporting bunks underhung from the center sill, and a cross tie supporting superstructure mounted on the center sill and comprising transverse Z-bars resting on the sill, and longitudinal Z-bars resting on the transverse Z-bars, an endless conveyer means working between the longitudinal Z-bars, roller supports journaled in said longitudinal Z-bars, and movable cross tie supports mounted on said longitudinal Z-bars.

21. In a track laying car, a car body, a pair of longitudinally disposed Z-bars mounted thereon, and oppositely disposed pairs of short angles hinged to the Z-bars

- and adapted to seat on said bars in raised position and swing below their top level in lowered position, rollers journaled in said bars, and conveyer cables running on said 5 rollers with one flight above the top level of said bars, and means for moving said cables.
22. In a track laying machine, two coupled cars, an endless conveyer means working lengthwise over the cars, driving means 10 for said conveyer, and cross tie supports between which the conveyer travels and which diverge toward the meeting ends of the cars, as and for the purposes described.
23. In a track laying machine, two coupled cars, cross tie supports on the cars, adapted to be raised or lowered, which diverge toward the meeting ends of the cars, a pair of endless conveyer cables traveling lengthwise across the cars between and with 20 their upper strands above said supports when the latter are in lowered position, and means to drive said conveyer cables.
24. In a track laying car, longitudinally arranged cross tie supports, endless conveyer cables traveling adjacent to said supports, means to drive said cables, means to lower the cross tie supports below the top level of the cable to permit the cross ties to be conveyed by the cables, a downwardly inclined 25 front extension on the car, two endless conveyer chains mounted to travel on said extension, and means to drive said chains by said cables, substantially as described.
25. A track laying car having a front 30 downwardly inclined extension, two endless chains carrying projections mounted to travel on said extension, endless conveyer cables mounted to travel lengthwise of the car, means to drive the chains by said cables, 35 means to drive the cables, and adjustable cross tie supports adapted in raised position to support the ties above the top level of the cables, substantially as described.
26. In a track laying car, longitudinal 40 cross tie supports formed in sections and adapted to be adjusted to raised or lowered positions, a pair of endless conveyer cables traveling adjacent to said supports, suitable anti-friction supports for said cables, a common driving means for both cables, and an 45 equalizing take-up means acting on both cables, substantially as described.
27. In a track laying car, longitudinal cross tie supports formed in sections and 50 adapted to be adjusted to raised or lowered positions, a pair of endless conveyer cables traveling adjacent to said supports, suitable anti-friction supports for said cables, a common driving means for both cables, an equalizing take-up means acting on both cables, and an independently adjustable tightening 55 sheave for each cable, substantially as described.
28. In a track laying car, longitudinal 60 supports for the cross ties thereon which comprise members adapted to be raised or lowered, a pair of endless conveyer cables mounted to travel on the car with their top flights above the level of said supports when lowered, a driving sheave an equalizing 70 sheave and a tightening sheave for each cable, means to independently adjust the tightening sheaves, a spring-pressed equalizing means connecting the equalizing sheaves for both cables, and adjustable supporting means to said equalizing and tightening sheaves, substantially as described. 75
29. In a track laying car, longitudinal supports for the cross ties thereon which comprise members adapted to be raised or lowered, a pair of endless conveyer cables mounted to travel on the car with their top flights above the level of said supports when lowered, a driving sheave an equalizing 80 sheave and a tightening sheave for each cable, means to independently adjust the tightening sheaves, an equalizing bar pivotally connected to both equalizing sheaves, a spring-pressed member connected to the center of said equalizing bar, means to adjust the spring tension on said equalizing bar, and adjustable supporting means for the equalizing and tightening sheaves, substantially as described. 85
30. In a track laying car, the combination 90 with vertically adjustable cross tie supports, of a pair of endless cables working lengthwise of the car adjacent to said supports, a driving sheave and a tightening sheave for each cable, means to independently adjust the tightening sheaves, and a spring-pressed tension equalizing means working on both cables and comprising means for simultaneously loosening or tightening both cables. 95
31. In a track laying car, longitudinal cross tie supports comprising vertically adjustable members, longitudinal conveyer cables working adjacent to said members and above their level when in lowered position, a sheave frame carried by the car and carrying driving sheaves equalizing sheaves and tightening sheaves, a screw adjusted spring tension means acting on each tightening sheave, a screw adjusted spring-pressed equalizing means acting on both equalizing sheaves, adjustable supports for the equalizing and tightening sheaves, and means for manipulating the said several screw adjustments for the spring-pressed 100 means, substantially as described. 105
32. A track laying car comprising a body having a structural metal center sill down-turned at its forward end, an extension sill spliced to the down-turned end of the center 110 sill, angles connected to the front end of said extension sill, a pair of spaced parallel bars disposed on each side of the extension sill and connected at their upper ends to the car body superstructure and at their 115 120
- 125 130

lower ends to said angles, endless sprocket chains working between said pairs of bars, suitable driving and idler sprockets for said chains, an adjustable tightening sprocket 5 for each chain, and an endless cross tie conveyer means movable over the car and adapted to drive the driving sprockets for said chains, substantially as described.

33. In a track laying car having a downwardly inclined tie and rail delivery extension at one end, and an elongated coupling element connected to the car and projecting forwardly over said extension into position to couple with other cars.

15 34. In a track laying car having a down-

wardly inclined tie and rail delivery extension at its front end, a coupling element mounted at an intermediate point on said extension, and an elongated coupling bar adapted to be pivotally connected to said element and to project forwardly of said extension into position to couple with rolling stock ahead of said track laying car. 20

In testimony whereof we affix our signatures.

ARTHUR DARSEN.
FELIX F. DOERING.
